UNITED STATES PATENT OFFICE.

GOTTLIEB TAUSSIG, OF NEW YORK, AND CARL WAGENFOHR, OF BROOKLYN,
NEW YORK.

EDUCATIONAL TOY.

1,340,304.

Specification of Letters Patent. Patented May 18, 1920.

Application filed December 5, 1917. Serial No. 205,617.

To all whom it may concern:

Be it known that we, GOTTLIEB TAUSSIG and CARL WAGENFOHR, citizens of the United States, residing in the city of New York, borough of Bronx, county of Bronx, and State of New York, and in the city of New York, borough of Brooklyn, county of Kings, and State of New York, respectively, have invented a certain new and useful 5 Educational Toy, of which the following is a specification.

This invention is an educational toy or game, and the object of the invention is a device of the character specified which 15 serves to both amuse and instruct the players and hold their attention in an interesting and intellectual manner.

Speaking generally, the invention, from a structural standpoint, embodies a casing, 20 a supporting member therein on which a disk is mounted for rotation, said disk being provided on its periphery with certain numbers or other designations, and with a series of depressions or pockets corresponding 25 in number, and arranged in juxtaposition, to the designations, means for manually rotating or spinning the disk, and a ball to which movement is imparted upon the spinning of the disk and which automatically 30 seeks one of the said depressions or pockets when the disk comes to rest.

The designations referred to may consist of numbers, letters, geographical locations, or any other suitable data.

35 Structural features of the invention, other than those adverted to, together with their functions and mode of operation, will be apparent from the following detailed description read in conjunction with the accompanying drawings.

In the accompanying drawings we have illustrated one practical embodiment of the invention, but the construction therein shown is to be understood as illustrative, 45 only, and not as defining the limits of the invention.

Figure 1 is a plan view of the toy, with the top or cover of the casing removed, and

Fig. 2 is a central section in the plane of line 2—2 of Fig. 1, with the cover in place.

Referring to the drawings, A designates a casing in the form of a cylindrical container open at its top but provided with a cover A'. A cylindrical strip B projects 55 upwardly from the annular walls of the

container and partakes of a position within cover A' to retain the cover and container in proper relation when the cover is in place. Secured in upstanding relation in the center of the bottom of the container is 60 a post or spindle C, about the lower portion of which extends a sleeve c, said sleeve and post C being rigid with one another and with the bottom of the container.

Upon post C is adapted to be rotatably 65 mounted the hub D' of a rotary member D, said hub resting upon the upper edge of sleeve c so as to maintain the disk elevated above the bottom of the container. Rotary member D may be made from metal, but, in 70 the interest of lightness and economy, it is preferably pressed up from papier-mâché. It embodies a substantially frusto-conical, peripheral section d which slopes from the outer periphery of the plate toward the hub, 75 and from the inner edge of section d a raised section d' extends to the hub, all of these parts being integral, so that the hub will serve to support the entire rotary member. There is thus formed in the upper face 80 of the rotary member, by the oppositely sloping portions d and d', an annular channel or runway in which is adapted to travel a ball E.

The upper surface of inclined section d 85 is divided into radially extending portions g, each of which is provided with a suitable designation, here shown as a numeral, and, while there may be any number of these portions, twenty-eight are shown and twenty-eight numerals are placed upon surface d in any arrangement which may be desired. In the annular line of intersection between inclined portions d and d' are provided a plurality of depressions or pockets 95 F, one of which is juxtaposed with each of the portions g.

Rotary member D, as stated, is mounted for rotation on post C, and such rotation may be imparted to said member by grasping the upstanding portion of hub D' and giving the same a sudden twist. As a result of this operation, member D is rapidly rotated and ball E spins around the upper surface thereof and is thrown to the outer 100 periphery of said member by centrifugal force. The diameter of member D is but slightly less than the inner diameter of container A, so that the walls of said container serve to keep the ball from being thrown 110

off and retain the same within the container, and resting upon rotary member D, during this rotation. When member D comes to rest after having been spun, ball 5 E will be caused to come to rest in one of the pockets F and will retain this position until the plate is again spun.

In playing the game, each player spins member D in his turn once and passes the 10 toy successively to the several players, until each has spun five times. As the ball comes to rest after each spin, the spinning player writes down the number opposite the pocket in which the ball came to rest after his spin, 15 and, after each player has spun five times, the one who has attained the highest aggregate is deemed the winner.

The game, when played in this manner, with numbers, is very helpful in assisting 20 the teaching of numbers to juveniles who are just learning numbers, as well as to older children who are in the process of learning addition.

It will be manifest that, by changing the 25 character of the designations on the marginal portion d of rotary member or disk D, the device may be utilized for various, but similar, forms of educational amusement. Thus, the designations may consist 30 of the letters of the alphabet, in which event each player is assigned the same number of letters. The disk is then spun as heretofore described by the several players in succession, the person succeeding in stopping the 35 ball first at the several letters to which he has been assigned being declared the winner of the particular contest. It will be manifest that, in utilizing the device in the manner just described, the players are familiarized with the letters of the alphabet.

In the event the designations are States, each person is assigned the same number of States, and the game thereafter played as in the case of employing letters, heretofore 45 described. The playing of the game in the foregoing manner familiarizes the players with geography.

In the interest of simplification and to avoid a substantial duplication of drawings, 50 and particularly as the modified forms of utilizing the invention do not call for any modification of the structure from a mechanical standpoint, it is not deemed advisable or necessary to illustrate different 55 forms of designations on the disk.

The mechanism of the toy of the present invention is extremely simple, an important commercial advantage being that the box or container in which rotary disk D is positioned, besides serving as a casing for the 60 disk when not in use, also serves as a mounting therefor when in use, as well as a circumferential guard to keep the ball from flying off the disk when the latter is rotated. The device is very compact, economical to 65 manufacture, and possesses high educational value. It will be observed, further, that, when cover A' is in place, it co-operates with container A to provide a complete housing, but the same can be readily removed to 70 allow of the playing of the game.

Having thus fully described the invention, what we claim as new, and desire to secure by Letters Patent, is:

An educational toy embodying a cylindrical casing provided with a closed bottom and an open top, a rigid upstanding post mounted in the center of the bottom of said casing and extending upwardly co-axially of the casing, and a bearing seat on said 80 post, in combination with a circular disk of slightly less diameter than the casing positioned interiorly of the casing appreciably below the upper edge of the side thereof with its outer circumference immediately adjacent the interior side wall of the casing, a tubular hub rigid with the disk and surrounding the post to provide a finger piece, whereby the disk may be spun around while supported on the seat of the 90 post, said disk being provided with an annular channel extending inwardly from its outer periphery for a portion of the radius of the disk, and at the lower portion of which channel is formed an annular series 95 of pockets into which a ball or sphere may come to rest when the centrifugal action of the spinning disk ceases, and said disk being lined radially to divide the surface thereof into radial spaces, each of which is provided with a designation or character corresponding to the juxtaposed pocket, the inner surface of the side wall of the casing above the disk serving as an abutment to preclude the ball from being thrown clear 100 of the disk during the rotation thereof.

In testimony whereof we have signed our names to this specification.

GOTTLIEB TAUSSIG.
CARL WAGENFOHR.
